RAILWAY WHEEL CHECKING DEVICE

Marion W. Gieskieng, Denver, Colo.

Application January 31, 1949, Serial No. 73,679

4 Claims. (Cl. 246—218)

1

This invention relates to a device for indicating both the loss of, and the condition of, railway car wheels, and has for its principal object the provision of a simple, accurate, and efficient device which will give a signal indication should a wheel of a passing train be broken or missing.

Another object of the invention is to provide means for giving a signal when badly worn or broken wheel treads or flanges pass the actuating mechanism.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a diagrammatic plan view of a section of railway track, illustrating one form of the missing wheel indicating mechanism applied thereto;

Figs. 2, 3, and 4 are diagrammatic views, illustrating the operation of the missing wheel indicator of Fig. 1;

Fig. 5 is a cross-section of a conventional rail, indicating a contact device which may be employed in connection with the missing wheel indicator of Fig. 1, if desired;

Fig. 6 is a second diagrammatic plan view of a section of railway track, illustrating an alternate form of the missing wheel indicator;

Fig. 7 is an enlarged, fragmentary cross-section through the track of Fig. 6, taken on the line 7—7, Fig. 6;

Fig. 8 is a cross-section of a conventional rail, indicating a form of contact device to be used for indicating worn wheel treads; and

Fig. 9 is a detail side view of the contact device employed in Fig. 8.

The device illustrated in Figs. 1 to 5, inclusive, is designed to indicate missing wheels on a passing train. The rails of a typical railway are indicated at 13 and 14. The device is installed by placing a relatively short insulated rail section 15 in the rail 13 opposite a relatively long insulated rail section 16 in the rail 14.

The rail sections 15 and 16 are electrically insulated from the respective rails 13 and 14 in any desired manner. The rails, however, are electrically bonded across the insulated rail sections 15 and 16 by means of bonding cables 17

2

and 18, respectively, so as not to interfere with block signal systems and other apparatus employing the rails as an electrical conductor.

The short insulated rail section 15 and the rail 13 are connected by means of circuit wires 19 with a transformer coil 20 through a source of current, such as a battery 21. The long insulated rail section 16 and the rail 14 are connected in circuit with a second transformer coil 22 through the medium of circuit wires 23.

The transformer coils 20 and 22 are inductively related so that surges of a current in the coil 20 will induce current in the coil 22. The induced current in the coil 22 is conducted by means of conductors 24 to any suitable signal relay device 25 for closing a circuit to produce an audible or visible signal.

The same circuit arrangement is repeated in reverse further along the rails 13 and 14, as shown at the right side of Fig. 1. In the second circuit, a relatively long insulated rail section 27 is installed in the rail 13, and a relatively short insulated rail section 26 is installed in the rail 14. The rails 14 and 13 are bonded across their respective insulated rail sections 26 and 27 by means of suitable bonding cables 28, and are connected to inductively related coils in a transformer 29 by means of suitable conductors 30. The transformer coil circuit from the short rail section 26 includes a current source 31, and the conductors 30 from the long section 27 include a suitable signal relay 32, as in the previously described circuit.

Let us assume that a car truck be moving to the right along the rails 13 and 14. A typical wheel and axle set of the truck is indicated in broken line at 33 in Figs. 2, 3, and 4. The right-hand wheel of the set 33 will roll onto the long rail section 16, as shown in Fig. 2. This short-circuits the transformer coil 22 through the conductors 23, the long section 16, and through the truck and the remaining wheels of the latter to the rail 14, as indicated by the broken-line circuit "A" in Fig. 2.

The wheel then rolls onto the short section 15, closing a circuit with the rail 13 through the conductors 19 with the transformer coil 20, as shown by the broken-line circuit "B" in Fig. 3, but since the coil 22 is short-circuited, no current or voltage can flow to the signal relay 25. The wheel now rolls from the short section 15, still maintaining the short-circuit "A" with the long section 16, as shown in Fig. 4. Therefore, no indication is given.

The same procedure is repeated as the wheels

roll over the sections 27 and 26. In the latter case the output coil of the transformer 29 is short-circuited by the wheels on the rail 13 and rail section 27, and the input coil is energized by the wheels on the rail 14, closing contact with 5 the section 26.

Now let us assume that the right wheel of the set is missing. No contact will be made with the long section 16 prior to the wheel contact with the section 15. The latter contact closes a circuit through the input transformer coil 20 and induces a voltage in the output transformer coil 22 to impress voltage on the signal relay 25 to give a signal indication.

Should the left wheel be missing, no current 15 with flow to the signal relay 25, but a signal will be given through the signal relay 32 when the remaining wheel of the set 33 rolls onto the short insulated rail section 26.

In Figs. 6 and 7 a form of missing wheel indicator is illustrated which obtains the same results as the circuits of Fig. 1 without requiring transformers or insulated track sections.

In this form a relatively short compressible plate 36 is mounted upon a bracket 37 inside the rail 34. The plate 36 extends beneath the path of the flange of a wheel traveling on the rail 34 so as to be depressed by flange contact. Depression of the plate 36 forces an insulating block 40 against a first contact blade 38 to cause it to 30 make contact with a second contact blade 39.

A relatively long, compressible contact plate 41 is mounted on a bracket 37 secured to the rail 35. The plate 41 is positioned in the path of the wheel flanges and, when depressed, acts to open a contact between a contact blade 42 and a blade 43 through the medium of an insulating block 44.

A conductor 45 leads from a signal relay 46 to the blade 43. A cross conductor 47 leads from the blade 42 to the blade 38. A battery conductor 48 leads from the blade 39 through a battery 49 to the signal relay 46.

Further along the track the same set-up is repeated and connected with a second signal relay 50. In the latter case, however, the short plate 36 is mounted adjacent the rail 35 and the long plate 41 is mounted adjacent the rail 34.

In operation, a pair of wheels on a common axle rolling to the right along the rails 34 and 35 will first contact the plate 41, opening the 50 circuit between the blades 42 and 43. The opposite wheel will then contact the plate 36, closing the circuit between the blades 38 and 39. Since the circuit is open, however, at blades 42 and 43, no signal current will flow to the signal relay 46.

Should the right wheel be missing, however, the plate 41 will not be depressed and the circuit will remain closed between the blades 42 and 43 so that when closed by the plate 36, a circuit will 60 be completed to the signal relay 46. Should the left wheel be missing, the circuit will not be opened beneath the second plate 41, so that a closure at the plate 36 will complete a circuit to the second signal relay 50.

The specific mechanism for making and breaking the circuits is simply illustrative. Other forms of switch mechanisms could be used to obtain the same final result. While the plates illustrated are operated by the wheel flanges, they could, of course, be similarly operated by any other part of the wheel.

The metallic contact between the wheels and the rails 13 and 14, and between the wheels and the insulated rail sections, will be usually suffi-

cient to operate the system of Fig. 1. If it is desired to avoid false indications caused by flat wheels, bouncing wheels, etc., a relatively long spring contact strip 51 can be mounted along the track sections 15, 16, 26, and 27, as shown in Fig. 5. The spring strip 51 projects sufficiently far above the rail to insure a perfect resilient contact with the wheel.

As the treads of railway wheels wear away, a groove is formed therein which allows the rim and the flange to project downwardly dangerously far below the top of the rail. In Fig. 8 a device is illustrated for detecting such a condition, comprising a cross bolt 52 which is extended through, and insulated from, the rail, indicated at 53 in Fig. 8.

A spring sleeve 54 is threaded on each extremity of the bolt 52. A resilient contact member 55 projects upwardly from each sleeve 54. The sleeves are adjusted on the bolt 52 to place the upper extremities of the contact members 55 at the legal limit for downwardly projecting rims and flanges. They are then set in this position in any desired manner, such as by means of a set screw 56 and a jam nut 57. The rail 53 and the bolt 52 are connected in any suitable indicating circuit so that when a defective wheel passes along the rail 53, a circuit will be closed with one or both the contact members 55, giving an indication of the defect.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A missing wheel detector for use on the two rails of a railway track, comprising: a first relatively long, wheel contact member positioned to be contacted by wheels passing along one rail; a second relatively short, wheel contact member positioned to be contacted by wheels passing along the other rail approximately opposite the mid-portion of the first contact member; and a signal circuit including both contact members; a first means actuated by said first contact when the latter is contacted to prevent current flow through said signal circuit; and a second means actuated by said second contact for causing current flow through said circuit unless said first means is actuated.

2. A missing wheel detector for use on the two rails of a railway track, comprising: a relatively long contact plate positioned adjacent one rail; a relatively short contact plate positioned adjacent the other rail opposite the first plate, said plates being positioned so that they will be depressed by wheels passing along said rails; contact-opening means positioned to be actuated by depression of the long plate; contact-closing means positioned to be actuated by depression of the shorter plate; and an electrical signal circuit including both said contact-opening means and said contact-closing means, said circuit being inoperative when both plates are depressed by passing wheels.

3. A railway wheel checking device for use on the two rails of a railway track, comprising: a first wheel-depressible device positioned adjacent the first rail; a second wheel-depressible device positioned adjacent the second rail; a circuit-opening switch actuated from and by depression of said first device; a circuit-closing switch actuated from and by depression of said second de-

vice, said devices being positioned in the path of wheels rolling along said rails, and being positioned directly opposite each other, said first device projecting both forwardly and rearwardly along said track beyond the extremities of said second device so that normal wheels in place on a common axle passing over said devices in either direction will depress the first device in advance of the second device and will maintain the first device depressed during the entire cycle of operation of said second device; and a signal circuit including both said circuit-closing switch and circuit-opening switch.

4. A railway wheel checking device for use on the two rails of a railway track, comprising: a first wheel-depressible device positioned adjacent the first rail; a second wheel-depressible device positioned adjacent the second rail; a circuit-opening switch actuated from and by depression of said first device; a circuit-closing switch actuated from and by depression of said second device, said devices being positioned in the path of wheels rolling along said rails, and being positioned directly opposite each other, said first device projecting both forwardly and rearwardly along said track beyond the extremities of said second device so that normal wheels in place on a common axle passing over said devices in either direction will depress the first device in advance of the second device and will maintain the first

20
25
30

device depressed during the entire cycle of operation of said second device; a signal circuit including both said circuit-closing switch and circuit-opening switch; a third wheel-depressible device positioned adjacent the second rail in spaced relation to the second wheel-depressible device; a fourth wheel-depressible device positioned adjacent the first rail in spaced relation to the first wheel-depressible device; a circuit-opening switch operable by said third device; a circuit-closing switch operable by said fourth device; and a second signal circuit including the latter circuit-opening and closing switches, said third device projecting forwardly and rearwardly along said track beyond the extremities of said fourth device so that when a set of normal wheels on a common axle passes in either direction over said third and fourth devices, the third device will be contacted in advance of the fourth device.
